RIBBED INSOLE

Hans C. Paulsen, Medford, Mass., assignor to
 B. B. Chemical Co., Boston, Mass., a corpora-
 tion of Massachusetts

Application October 22, 1945, Serial No. 623,696

16 Claims. (Cl. 36—22)

1

This invention relates to insoles and, more particularly, to insoles provided with sewing ribs and to strips for use in forming sewing ribs on insoles to adapt them for use in the manufacture of welted shoes.

An important object of the present invention is to provide an improved insole of relatively thin material having a strong upstanding sewing rib permanently attached to its outer surface. A further object of the invention is to provide improved strips for use in forming sewing ribs on insoles.

To the accomplishment of these objects, the invention provides, in accordance with one aspect, an improved insole comprising an insole-shaped body of relatively thin material provided on its outer surface with a sewing rib which extends around the marginal portion of said insole body. The sewing rib, as herein illustrated, comprises an integral strip of flexible sheet material folded to form a four-ply rib having integral flanges extending from opposite sides thereof.

The strip, as illustrated herein, is coated on one side with cement, preferably a pressure-responsive cement, and the folding is done in a direction to bring the cemented surface against itself to cause the layers to adhere to each other to form a two-ply layer. The two-ply layer is then folded to produce a four-ply portion with remaining portions of the strip extending therefrom. In order to hold the plies of the four-ply portion together, stitches are inserted into said portion, the stitches passing through at least three plies thereof. The stitches also establish a line of division between the four-ply portion and the remaining portions of the strip projecting therefrom. The strip is now ready to be attached to an insole body to provide a sewing rib thereon.

In attaching the strip to the insole body, the four-ply portion is bent upwardly substantially at right angles to the plane of said insole body to provide a four-ply upstanding sewing rib and the remaining portions of the strip, which project from the four-ply portion, are simultaneously pressed flat against the surface of the insole body at opposite sides of the rib to form integral inner and outer flanges, the outer flange preferably terminating at, or a short distance inwardly of, the edge of the insole body and the inner flange covering a substantial portion of said insole body inwardly of the rib.

The integral ribbed strip, as herein illustrated, is attached to the outer surface of the insole body by means of the pressure-responsive cement on

5 the strip and a band of cement, preferably the same kind of cement, extending around the marginal portion of said outer surface. The attachment of the ribbed strip to the insole body is particularly strong by reason of the wide inner flange which not only helps to secure the strip permanently to the insole body but serves also to reinforce said insole body. The outer flange assists in maintaining the multi-ply rib in its 10 upstanding position or in returning the rib to such position if it is bent outwardly during the lasting or inseaming operations in the manufacture of the shoe. The illustrated rib is well adapted to receive stitches, staples or other fastening means which may be used in the operations referred to and, owing to the fact that the rib and flanges are integral, there is practically no danger of the rib tearing away from the flanges under the strains exerted by the upper 15 during or after the lasting and inseaming operations.

In accordance with another aspect, the invention provides an improved ribbed strip for use in forming sewing ribs on insoles comprising a single 20 strip of flexible sheet material of indefinite length folded to provide a four-ply portion or rib extending lengthwise of the strip and having portions extending therefrom which form integral flanges at opposite sides of the rib, the lower 25 surfaces of said flanges being coated with cement, preferably a pressure-responsive cement.

The above and other features and aspects of the invention, including modifications of the ribbed strip, will appear more fully from the following detailed description when read in connection with the accompanying drawings and will thereafter be pointed out in the claims.

In the drawings,
 Fig. 1 is an end view of a single strip of sheet 40 material folded over and stitched to form a four-ply portion;

Fig. 2 is a plan view of an end portion of the strip;

Fig. 3 is a perspective view on a reduced scale 45 illustrating how the strip may be wound upon a reel for shipment after it has been folded and stitched;

Fig. 4 is a perspective view of the strip attached to an insole with the four-ply portion turned upwardly to form a sewing rib.

Fig. 5 is a transverse sectional view of the insole and strip on the scale shown in Fig. 1, the section being taken on the line V—V of Fig. 4;

Fig. 6 is an end view similar to Fig. 1 showing 50 a modified form of strip;

Fig. 7 is a sectional view of an insole, similar to Fig. 5, with the strip of Fig. 6 attached thereto;

Fig. 8 is an end view of another modified form of strip;

Fig. 9 is a sectional view of an insole showing the strip of Fig. 8 attached thereto;

Fig. 10 is an end view of another modification of the folded strip;

Fig. 11 is a sectional view of an insole showing the strip of Fig. 10 attached thereto;

Fig. 12 is an end view of still another modified form of folded strip;

Fig. 13 is a sectional view of an insole showing the strip of Fig. 12 attached thereto;

Fig. 14 is an inverted end view of a further modification of the folded strip; and

Fig. 15 is a sectional view of an insole with the strip of Fig. 14 attached thereto.

In making the integral ribbed strip of the present invention for providing sewing ribs on insoles, a relatively wide strip S of indefinite length is provided composed of a single strip of flexible sheet material, such as Gem duck, canvas or similar fabric, the lower surface of the strip, as viewed in Fig. 1, being coated with cement C, preferably a pressure-responsive cement such as rubber cement, neoprene, latex or other cements comprising synthetic rubber-like materials. The strip is folded, as illustrated in Fig. 1, to form a four-ply portion R which is subsequently to form the sewing rib, the portion R extending lengthwise of the strip along one margin thereof. The remaining portions of the strip extend from one side of the four-ply portion after folding, these remaining portions in Fig. 1 comprising a single ply layer I and a two-ply layer F.

After the strip has been folded as described, a row of stitches 20 is inserted into the four-ply portion R, the stitches passing through all four plies and securing the plies permanently together and also establishing a line of division between the portion R and the remaining portions I and F extending therefrom. As illustrated in Figs. 1 and 2, the strip is initially folded so that the cemented lower surface is brought against itself thereby causing the layers to adhere to each other to form a two-ply layer which is then folded again to form the four-ply layer R which, in turn, is secured together by the stitches 20. The strip S in the condition shown in Figs. 1 and 2 is ready for attachment to an insole and may be wound upon a reel 22, as illustrated in Fig. 3, to facilitate handling the strip or shipping it to manufacturers.

The strip S is attached to an insole 24, as illustrated in Fig. 4, the strip being fed from the reel 22 and applied progressively to the outer surface of the insole by a machine adapted to attach the strip, such a machine being disclosed in Letters Patent of the United States No. 2,383,560, granted August 28, 1945, upon an application filed in my name, although other machines may be used if desired. As the folded strip S is fed from the reel 22, the four-ply portion R passes through a guide on the machine which bends said portion upwardly along the line of stitches 20 substantially at right angles to the body of the insole, the machine simultaneously pressing the integral flange portions I and F of the strip against the insole to provide an insole having an upstanding four-ply sewing rib R having integral inner and outer flanges I and F, the outer flange F terminating substantially at the edge of the insole around the forepart thereof

and terminating a short distance inwardly of the edge of the insole at its shank portion. The inner flange I, as shown in Fig. 4, preferably covers a substantial portion of the insole body inwardly of the rib and thus provides a strong bond between the strip and the insole as well as serving to reinforce the insole body in place of an overall canvas reinforcement which is sometimes used on thin flexible insoles of relatively cheap material. The outer surface of the insole 24 is provided with a band of cement 26, preferably a pressure-responsive cement of the same type as is applied to the lower surface of the strip, so that when the strip is fed to the insole by the ribbed-strip-attaching machine, the flanges F and I will adhere firmly to the insole body as they are pressed against said body by the machine. The ribbed strip extends around the marginal portion of the insole from approximately the heel-breast line at one side thereof to the heel-breast line at the opposite side. The machine is provided with a cut-off knife which severs the strip at the heel-breast line after it has been attached to the insole body as described. As illustrated in Fig. 1, the outer flange F of the strip consists of a two-ply layer while the wide inner flange I comprises a single-ply layer.

Figs. 6 and 7 illustrate a modified form of ribbed strip S which may be used to provide a sewing rib on insoles. The strip of Fig. 6 is folded over, as described above, to form a two-ply layer which, in turn, is folded to form a four-ply layer R having two-ply layers F and I extending from one side thereof. Stitches 20 are inserted through the four-ply layer R to hold the plies together and form a line of division between the portion R and the extending portions F and I. The strip is attached to an insole 24, as illustrated in Fig. 7, the four-ply portion R forming the upstanding rib and the two-ply portions F and I forming outer and inner flanges, respectively, integral with the rib, the two-ply outer flange F terminating inwardly of the edge of the insole at the shank portion, as shown in Fig. 7, and the two-ply inner flange I, together with a single ply portion K of the strip, covering a substantial portion of the insole body inwardly of the rib R. Pressure-responsive cement C is provided on the lower surface of the strip and, when brought into contact with the same kind of cement on the insole body, causes the ribbed strip to become permanently attached to said insole body.

The strips illustrated in Figs. 8 to 15, inclusive, are modifications of the strips shown in Figs. 1 to 7. The strip S of Fig. 8 has pressure-responsive cement C on its upper surface and is folded over at one margin to form a four-ply layer R, a two-ply layer T being first formed and secured by stitches 28, after which the remaining portions of the strip are folded back upon the two-ply layer to form the four-ply layer R. As shown in Fig. 8, stitches 20 are inserted through the four-ply layer R and the remaining portions of the strip extend outwardly from one side of the four-ply layer to form single ply inner and outer flanges I and F integral with the rib R. The ribbed strip S is attached to the insole 24, as shown in Fig. 9.

In Fig. 10, the strip is folded to form a three-ply portion R having single-ply portions I and F projecting from the opposite sides thereof. Stitches 20 secure the three plies of the portion R together. The strip is applied to the insole 24, as shown in Fig. 11, the portion I forming the

fourth ply of the rib R and the remaining portion thereof forming an integral single ply inner flange I. The pressure-responsive cement C on the bottom surface of the strip and the same kind of cement 26 on the insole causes the ribbed strip to adhere permanently to the outer surface of the insole, as shown in Fig. 11.

In Fig. 12, the strip S is folded to form a four-ply layer R having two single-ply layers F and I projecting from one side thereof. Stitches 20 secure the four plies of the portion R together. The ribbed strip is attached to the insole 24, as shown in Fig. 13, the single-ply portion F forming the outer flange and the wide single-ply portion I forming the inner flange.

Figs. 14 and 15 illustrate a further modification of the ribbed strip. As shown in Fig. 14, the strip S is folded to form a three-ply portion R having a single-ply layer F extending from one side thereof and a wide single-ply layer I extending from the opposite side thereof. Pressure-responsive cement C is on the upper or attaching surface of the strip, as viewed in Fig. 14. Stitches 20 secure the three plies of the rib together. The strip is applied to an insole 24, as illustrated in Fig. 15, the single-ply portion F forming the outer flange and the wide single-ply portion I forming the inner flange. The cement C and 26 on the strip and insole body, respectively, causes the strip to adhere permanently to said insole body.

Having thus described my invention, what I claim as new and desire to secure by Letters Patent of the United States is:

1. An insole comprising an insole-shaped body, a sewing rib extending around the marginal portion of said insole body, said rib consisting of a single integral strip of sheet material folded to form a four-ply portion with the remaining portions of the strip extending from opposite sides of said four-ply portion, said four-ply portion extending substantially at right angles to said insole body to form an upstanding rib, and said remaining portions forming inner and outer flanges integral with the rib, said flanges being secured by cement alone to the marginal portion only of the insole-shaped body.

2. An insole comprising an insole-shaped body, a sewing rib secured to the marginal portion of said insole body, said rib consisting of a single strip of flexible sheet material folded to form a four-ply portion with the remaining portions of the strip extending from opposite sides thereof, said four-ply portion extending substantially at right angles to the insole body to form a four-ply upstanding sewing rib, and said remaining portions being secured flat against the marginal portion of said insole body to form inner and outer flanges integral with the rib, said inner flange covering a substantial portion of the insole body but leaving the central portion thereof uncovered.

3. An insole comprising an insole-shaped body, a sewing rib secured to the marginal portion only of said body by cement alone, said rib consisting of a single integral strip of sheet material folded over upon itself to form a four-ply portion extending lengthwise of the strip, said four-ply portion extending substantially at right angles to the remaining portions of the strip with its plies in contact with each other throughout to provide a solid upstanding four-ply rib, said remaining portions forming inner and outer flanges integral with the rib, and stitches extending through the

four-ply rib for holding the plies permanently in contact with each other.

4. An insole comprising an insole-shaped body, a sewing rib secured to the marginal portion only of the outer surface of the insole body, said rib consisting of a single integral strip of flexible sheet material a portion of which is folded over upon itself to form a four-ply portion extending lengthwise of the strip, said four-ply portion being located between the opposite margins of the strip and extending substantially at right angles to the plane of the insole body to provide an upstanding four-ply rib, the marginal portions of the strip at opposite sides of the rib forming inner and outer flanges integral with the rib, and cement between plies of the rib for holding said plies in engagement with each other throughout the height of the rib.

5. An insole comprising an insole-shaped body, a sewing rib extending around the marginal portion of said body, said rib consisting of an integral strip of flexible sheet material folded to form a four-ply portion extending lengthwise of the strip with the plies in contact with each other throughout said portion, said four-ply portion being located at an intramarginal portion of the strip and extending substantially at right angles to the body of the insole to provide an upstanding four-ply solid rib integral with the strip, lateral portions of the strip at each side of said rib forming integral inner and outer flanges at the base of the rib, stitches extending through the multiply rib for holding the plies together, and cement between said inner and outer flanges and the marginal portion only of the body of the insole for securing the rib permanently to said marginal portion.

6. An insole comprising an insole-shaped body having a substantially smooth outer surface, a sewing rib secured to the marginal portion only of said outer surface, said rib consisting of a single integral strip of sheet material folded over to form a four-ply portion extending lengthwise of the strip with plies in continuous contact with each other, said four-ply portion being located between the opposite margins of the strip and extending substantially at right angles to said margins to provide a four-ply upstanding rib, said margins forming inner and outer flanges at the base of the rib integral with said rib, and stitches passing through at least three plies of the rib for holding the plies permanently together.

7. An insole comprising an insole-shaped body, a sewing rib secured to the marginal portion only of said body by cement alone, said rib consisting of a single integral strip of flexible sheet material folded over upon itself to form a two-ply outer flange, a four-ply rib and an inner flange comprising only a single-ply throughout its width, said four-ply rib being positioned substantially at right angles to the two-ply and single-ply flanges to provide an upstanding four-ply rib integral with said flanges, and stitches passing through at least three plies of the rib.

8. An insole comprising an insole-shaped body, a sewing rib extending around the marginal portion only of the insole body, said rib consisting of a single integral strip of flexible sheet material folded over upon itself to form a two-ply portion extending lengthwise of the strip, said two-ply portion being folded over upon itself to form a four-ply portion adjacent to one margin of the strip and having a two-ply layer and a single layer projecting therefrom, said four-ply portion extending at right angles to the two-ply and single

layers to provide an upstanding four-ply rib, said two-ply layer forming an integral outer flange at the base of the rib and said single layer forming an integral inner flange at the base of said rib, said outer flange terminating at, or a short distance inwardly from, the edge of the insole body and said inner flange covering a substantial portion of the insole body inwardly of the rib but leaving a portion of said insole body uncovered, stitches extending through said rib adjacent to its base and passing through all four plies thereof, and cement between said inner and outer flanges and the insole body for securing the rib permanently to said insole body.

9. An insole comprising an insole-shaped body, a sewing rib secured to the marginal portion only of said body, said rib consisting of a single integral strip of sheet material folded over upon itself to form a two-ply layer, a portion of said two-ply layer being folded over upon itself to form a four-ply layer having two two-ply layers extending from opposite sides thereof, said four-ply layer being located substantially at right angles to the two-ply layers to provide an integral upstanding four-ply rib, said two-ply layers forming integral inner and outer flanges at the base of said rib, the upper ply of said inner flange extending inwardly beyond the inner flange to cover a substantial portion of the insole body inwardly of said flange but not the entire insole body inwardly of the rib, and stitches in the rib passing through at least three plies thereof for securing the plies together.

10. An insole comprising an insole-shaped body, a sewing rib extending around the marginal portion only of the insole body, said rib consisting of a single integral strip of sheet material a portion of which is folded over upon itself widthwise to form a two-ply layer, part of said two-ply layer being folded over upon itself widthwise to form a four-ply portion, said four-ply portion being located substantially at right angles to the remaining portions of the strip to provide an integral upstanding four-ply rib, said remaining portions consisting of the portions of said two-ply layer located at opposite sides of said four-ply portion, one of said two-ply layers having a single-ply portion extending beyond it, said two-ply layers forming integral inner and outer flanges at the base of the four-ply rib and said single-ply extending portion forming an extension of said inner flange and covering a substantial portion of the insole body inwardly of said flange but leaving the central portion of the insole body exposed, stitches passing through the rib adjacent to its base for holding the plies together in an upstanding position, and pressure-responsive cement between the insole body and said inner and outer flanges including the single-ply extension of the inner flange for securing the strip permanently to the insole body.

11. An insole comprising an insole-shaped body, a sewing rib secured to the marginal portion only of the insole body by cement alone, said rib consisting of a single integral strip of flexible sheet material folded to form a two-ply layer, portions of the layers of said two-ply layer being folded back again upon themselves to form a four-ply portion having two single-ply layers projecting from opposite sides thereof, said four-ply portion being located substantially at right angles to the single-ply layers to provide an upstanding four-ply rib, said single-ply layers forming inner and outer flanges integral with said rib, and stitches inserted in the rib and passing through at least

three plies thereof for holding the plies together.

12. A ribbed strip for attachment to insoles to provide sewing ribs thereon comprising a single integral strip of flexible sheet material folded to form a four-ply rib with flanges integral with the rib extending from opposite sides thereof.

13. A strip for providing sewing ribs on insoles comprising a single integral strip of sheet material folded over upon itself to form a four-ply portion extending lengthwise of the strip, said four-ply portion being located at one margin of the strip with the remaining portions of the strip projecting therefrom, said four-ply portion being adapted to be turned substantially at right angles to said remaining portions to provide an upstanding four-ply rib, and said remaining portions being adapted to form integral flanges at opposite sides of the base of said rib, the lower surfaces of said flanges having dry pressure-responsive cement thereon whereby the strip is adapted to be permanently secured to the outer surface of an insole.

14. A strip for providing sewing ribs on insoles comprising a single integral strip of flexible sheet material folded over upon itself to form a four-ply portion extending lengthwise of the strip with the remaining portions of the strip projecting from said four-ply portion, said four-ply portion being adapted to be turned upwardly substantially at right angles to said remaining portions to provide an upstanding four-ply rib, said remaining portions being adapted to form integral inner and outer flanges at the base of said rib, and cement between the plies of said rib for holding said plies in engagement with each other throughout the entire rib.

15. A strip for providing sewing ribs on insoles comprising a single integral strip of sheet material a marginal portion of which is folded over upon itself to form a two-ply layer, said layer being folded over upon itself again to form a four-ply layer having a two-ply layer and a single-ply layer extending therefrom, stitches extending through the four-ply layer, said four-ply layer being adapted to be turned upwardly along the line of stitches substantially at right angles to the two-ply and single-ply layers to provide an upstanding four-ply rib, said two-ply layer being adapted to form an outer flange at the base of said rib integral therewith when the latter is turned upwardly, and said single-ply layer being adapted to form an integral inner flange at said base, the outer flange being approximately equal in width to the feather portion of the insole and the inner flange being considerably wider than said outer flange but narrower than the portion of the insole which lies inside the rib.

16. A strip for providing sewing ribs on insoles comprising a single integral strip of flexible sheet material a marginal portion of which is folded over upon itself widthwise to form a two-ply layer, said two-ply layer being folded over upon itself again to form a four-ply layer having two two-ply layers extending from one side thereof with the upper ply of one of said two-ply layers projecting beyond said two-ply layer, stitches passing through said four-ply layer and separating said layer from said two-ply layers, said four-ply layer being adapted to be turned upwardly along the line of stitches substantially at right angles to the two-ply layers to provide a four-ply upstanding rib integral with said two-ply layers, said two-ply layers being adapted to form integral inner and outer flanges at the base of the rib

when it is turned upwardly, the two-ply layer having the extending upper layer forming the inner flange, said upper layer extending inwardly beyond said inner flange and being adapted to cover a substantial portion of the insole body inwardly of the rib.
